UNITED STATES PATENT OFFICE.

ADELINE J. CORSCADEN, OF PHILADELPHIA, PENNSYLVANIA, ADMINISTRATRIX OF THOMAS CORSCADEN, DECEASED.

PUNCHING-DIE.

SPECIFICATION forming part of Letters Patent No. 629,429, dated July 25, 1899.

Application filed October 3, 1898. Serial No. 692,460. (No model.)

To all whom it may concern:

Be it known that THOMAS CORSCADEN, deceased, late of Philadelphia, Pennsylvania, did invent an Improvement in Punching-Dies, of which the following is a specification.

The invention has reference to dies for punching rivet or bolt holes in the rims of sheet-metal pulleys; and it consists of certain improvements, which are fully set forth in the following specification and shown in the accompanying drawings, which form a part thereof.

The object of this invention is to provide suitable devices for punching holes in the flanged portions of the rim-segments of sheet-metal pulleys.

In the manufacture of sheet-metal pulleys—such, for example, as illustrated in patents to Corscaden, No. 595,559, dated December 20 14, 1897, and No. 575,106, dated January 12, 1897—the rims are formed of four sections having internal flanges which are bolted together and to the spoke-arms, and, furthermore, the two semicircular portions of the rim so formed are secured together by rim-clamps, sections of which are riveted to the internal flanges of the rim. It is essential in the manufacture of wheels of this character that the flanges shall be properly perforated 25 or punched, so as to be brought into proper alinement with the punched ends of the spoke-arms and, further, so that the holes in the flanges and ends of the adjacent segments shall come in accurate alinement, whereby 30 the proper assembling of the several parts making up the complete article is insured. To enable this result to be speedily accomplished, the invention comprehended in this application is especially designed for punching the necessary holes in the internal flange 35 of the rim-segment constituting one-quarter of the full rim of the pulley.

In carrying out this invention a set of punching-dies is provided, one part of which, preferably the lower, is provided with a series of die-plates, preferably adjustable radially to and from a common center, and also a suitable clamping device for holding the rim-segment in position upon said die-plates. The 45 other portions of the dies are provided with

corresponding guides, in which are adjustably secured suitable punches adapted to operate in conjunction with the punch-plate of the lower dies. By employing dies for simultaneously punching all of the holes in a rim-segment while the same is held in proper curved position absolute accuracy in the location of the holes is secured, and the rim of the pulley runs true in the finished article. The adjustment of the die-plates and punches 55 enables rims corresponding to different diameters of pulleys to be punched, and consequently one set of dies suffices for punching the rims of a great many different sizes of pulleys.

The invention will be better understood by reference to the accompanying drawings, in which—

Figure 1 is an elevation of the improved dies. Fig. 2 is a plan view of the lower die. Fig. 3 is an inverted plan view of the upper die. Fig. 4 is a sectional elevation on line *xx* of Fig. 1, and Fig. 5 is a cross-section of one of the rim-segments.

A is the base-plate or frame of the lower die and is provided with a series of radial guides *B'B'*, arranged at angles of thirty degrees apart; but the invention is not confined to any particular number or angular arrangements of these guides. In these guides are 75 arranged, respectively, adjustable blocks *C'C'*, which are movable to or from the center of radiation of the guides and adapted to be locked in various positions by means of spring-actuated plugs *d*, operating in connection 80 with the fixed perforated plates *D*, arranged in the lower portions of the said guides. By employing two of these plugs a greater possible adjustment is secured with a limited number of holes or perforations in the plates 85 *D*. Broadly considered, it is immaterial to the invention what means are employed for adjusting the blocks in position upon their guides. The upper portions of these blocks are provided with punch die-plates *e*, which 90 may be made in any suitable manner, as is well known in punch and die work. In the blocks *C* and *C'* two punch-plates are preferably employed; but in the case of the blocks *C'* one punch-plate suffices. It is to be un- 95 100

derstood that it is immaterial how the plates forming the die to receive the punches are formed.

E, E', and E² are stripper-plates which overhang the punch-plates and are respectively secured to the upper portions of the blocks C, C', and C² and so arranged as to permit the flange R of the pulley-segment to pass between said stripper-plates and the punch-plates, as is clearly shown in Fig. 4. The two blocks C², arranged diametrically opposite, are provided with abutments having V-shaped recesses c to receive the ends of rim-segments and hold them in position in all directions except from the side in which they are entered. These abutments may be formed in any other suitable manner desired so long as they perform the function of receiving and holding the ends of the rim-segments. They operate in effect as one jaw of a clamp, the other jaw thereof being the adjustable lever F, having the clamping-screw f and hinged to the central block C. It will be observed that when this hand-clamp f is thrown upward the rim r of segment R may be placed in the die, as indicated in dotted lines in Fig. 2, the flange passing under the strippers and over the die-plates and the ends of the rim or periphery being received in the V-shaped recess c. When the lever-clamp f is thrown down into the position shown in Figs. 2 and 4, the rim is pressed forward into position and touches the upper edges of each one of the blocks C and C', said upper edges being made curved, as indicated, so as to have but a limited point of contact. It will be observed also that these outer edges are inclined inward somewhat and that the portions of the blocks below the upper and outer edges are recessed to enable the rim-flanges to be placed in position without contact with the lower portions of the blocks C. In practice it is customary to have the curvature of the rims of a slightly-less diameter than in the finished wheel, so that when they are clamped in position by the central clamp the intermediate portions are caused to adjust themselves to the outer upper edges of the intermediate blocks C and C'. This insures the rim lying in the proper shape, so that the punched holes will be accurately located as to position.

Attention is called to the fact that the two holes which are punched in the rim corresponding to the blocks C are for attachment to the ends of the spoke-arms, while the single hole corresponding to the blocks C' are intended for riveting together the two flanges of the adjacent rim-segments without connection to any spoke-arms, but rather for the purpose of reinforcing the rim structure. Attention is also called to the fact that the radial adjustment of the blocks C' is not made with the same capacity as the blocks C and C², because when the diameter of the pulley is sufficiently reduced so that the space between the outer ends of the spoke-arms does not become excessive the riveting of the two

flanges together intermediate of the spoke-arms may be dispensed with. For this reason the long radial guides B, B² and J, J² and the short radial guides B', J' are employed, as shown, the latter and their blocks B', J' only being employed for pulleys of large diameters.

The two holes to be punched in the rim adjacent to the ends are preferably arranged at a greater distance apart than in the case of the holes for attachment to the spoke-arms, this being to enable the proper connection to the rim-clamps, though the particular distance apart of these holes or the number of the holes is immaterial to this invention.

Referring now to the upper dies, the base plate or frame H is provided on its under side with a series of radial guides J, J', and J², corresponding to the several guides B, B', and B² of the lower die. These guides are respectively provided with blocks I, I', and I², which are adjustable therein and adapted to be located in various positions by the employment of the spring-actuated plugs k and perforated plates K, corresponding to the plugs d and perforated plates d of the lower die. The blocks I and I² are each respectively provided with two punches L and L², adapted to the punch-plates of the blocks C and C² of the lower die. Likewise the blocks I' of the upper die are provided with punches L' to correspond with the punch-plate in the blocks C' of the lower die. The upper-die frame is further furnished with two steel pins g, which are received in sockets or recesses G in the rear end of the frame of the lower die, as shown in Fig. 4, the object of which is to properly hold the dies in alinement at or about the time of the punching operation.

The invention is not confined to any special method or means for adjustment of the blocks C, C', and C² and I, I', and I², as any other suitable means of adjustment other than that herein set out may be employed, if so desired. While the construction herein shown is preferred as excellently adapted to the purpose, the invention is not confined to the specific details, as the parts may be modified without departing from the essential features of the invention. It is further to be understood that while it is preferred to punch the rim to receive the rim-clamp this is not essential, and therefore the blocks C² may have the stripper E² and punch-plates omitted, and likewise the blocks I² and their punches may be omitted from the upper dies. It is further to be considered that the guides, blocks, and punches for punching the intermediate holes for riveting the arms between the points of connection with the spoke-arms may be entirely omitted, if so desired, and the punches corresponding to the blocks C and I alone employed.

Having now described the invention, what is claimed as new, and desired to be secured by Letters Patent, is—

1. The combination of two frames relatively

- movable to and from each other, a series of radial guides upon the adjacent surfaces of said frames, adjustable blocks in said guides, a clamp device for clamping the work upon the blocks corresponding to one of said frames, and punching devices having one element carried by the blocks on one of the frames and the other element carried by the blocks on the other frame.
- 10 2. The combination of two frames relatively movable to and from each other, a series of radial guides upon the adjacent surfaces of said frames, adjustable blocks in said guides, a clamp device for clamping the work upon the blocks corresponding to one of said frames, punching devices having one element carried by the blocks on one of the frames and the other element carried by the blocks on the other frame, and locking devices for locking the blocks in their adjusted radial position.
- 15 3. The combination of two frames relatively movable to and from each other, a series of radial guides upon the adjacent surfaces of said frames, adjustable blocks in said guides, a clamp device for clamping the work upon the blocks corresponding to one of said frames, punching devices having one element carried by the blocks on one of the frames and the other element carried by the blocks on the other frame, and stripper-plates carried by the blocks upon which the work is clamped for holding the said work against displacement during the punching operation.
- 20 4. The combination of two frames relatively movable to and from each other, a series of radial guides upon the adjacent surfaces of said frames, adjustable blocks in said guides, a clamp device for clamping the work upon the blocks corresponding to one of said frames, punching devices having one element carried by the blocks on one of the frames and the other element carried by the blocks on the other frame, and means disposed upon each side of the radial guides and blocks upon which the work is clamped for receiving and holding the ends of the semicircular or curved blank to be punched.
- 25 5. The combination of two frames relatively movable to and from each other, a series of radial guides upon the adjacent surfaces of said frames, adjustable blocks in said guides, a clamp device for clamping the work upon the blocks corresponding to one of said frames, punching devices having one element carried by the blocks on one of the frames and the other element carried by the blocks on the other frame, means disposed upon each side of the radial guides and blocks upon which the work is clamped for receiving and holding the ends of the semicircular or curved blank to be punched, and adjusting devices for adjusting the means for holding the ends of the work to or from each other to suit different diameters of pulley-rims.
- 30 6. The combination of two frames relatively movable to and from each other, a series of long radial guides formed thereon, intermediate short radial guides also formed thereon and arranged alternately with the long radial guides, a series of adjustable blocks adapted to the said guides, means for holding the blocks in various positions in the guides, and punching devices carried by the blocks the punches thereof being secured to the blocks on one of the frames and the dies secured to the blocks on the other frame.
- 35 7. The combination of two frames relatively movable to and from each other, a series of long radial guides formed thereon, intermediate short radial guides also formed thereon and arranged alternately with the long radial guides, a series of adjustable blocks adapted to the said guides, means for holding the blocks in various positions in the guides, punching devices carried by the blocks the punches thereof being secured to the blocks on one of the frames and the dies secured to the blocks of the other frame, and suitable clamping devices for holding the work to be punched upon the blocks of the frame having the die portions of the punching devices.
- 40 8. The combination of two frames relatively movable to and from each other, a series of long radial guides formed thereon, intermediate short radial guides also formed thereon and arranged alternately with the long radial guides, a series of adjustable blocks adapted to the said guides, means for holding the blocks in various positions in the guides, punching devices carried by the blocks the punches thereof being secured to the blocks on one of the frames and the dies secured to the blocks of the other frame, suitable clamping devices for holding the work to be punched upon the blocks of the frame having the die portions of the punching devices consisting of two radial adjustable jaws for receiving and holding the ends of the semicircular rim to be punched and a clamp carried by one of the blocks intermediate of said jaws for forcing the semicircular rim against the outer edges of the blocks and into the jaws.
- 45 9. The combination of two frames relatively movable to and from each other, a series of blocks secured to one of said frames and having their outer edges arranged in a semicircle, punch-dies secured to said blocks, clamping devices for holding a semicircular pulley-rim upon said blocks in position to be punched, and a series of punches carried by the other frame and adapted to operate in connection with the punch-dies of the blocks of the other frame.
- 50 In testimony of which invention I hereunto set my hand.
